(57) **CLAIM**

The ornamental design for a wireless cantilever head mounted display with adjustable optical system, as shown and described.

DESCRIPTION

A portion of the disclosure of this patent document contains material which is subject to copyright protection. This patent

document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

FIG. 1 is a depiction of the complete wireless cantilever HMD.

FIG. 2 is a right side view of the wireless cantilever HMD.

FIG. 3 is a left side view of the wireless cantilever HMD.

FIG. 4 is a top view of the wireless cantilever HMD.

FIG. 5 is a bottom view of wireless cantilever HMD.

FIG. 6 is a front view of wireless cantilever HMD.

FIG. 7 is a rear view of the complete wireless cantilever HMD.

FIG. 8 is a rear view of the wireless cantilever HMD with the rear compartment removed.

FIG. 9 is the same as FIG. 8 with the rear most components of the optical mounting system removed.

FIG. 10 is the same as FIG. 9 with the adjustable interpupillary lens supports and mounting frame removed.

FIG. 11 is the same as FIG. 10 with the complete optical system and head frame removed.

FIG. 12 is the same as FIG. 11 with the screen and screen bezel removed.

FIG. 13 is the same as FIG. 12 with the screen control board mount removed.

FIG. 14 is a cutaway perspective depiction of the complete optical system.

FIG. 15 is the same as FIG. 14 with the rear most components of the optical mounting system removed; and,

FIG. 16 is the same as FIG. 15 with the adjustable interpupillary lens supports and mounting frame removed.

This wireless cantilever head mounted display (HMD) is to be used for virtual reality and augmented reality applications as well as all other variations in the reality-virtuality continuum. The HMD allows the user to explore such mixed reality in a stationary setting or in a roaming mode within motion capture environments.

1 Claim, 10 Drawing Sheets
